LIGHTNING ARRESTER

Edward F. W. Beck, Pittsburgh, Pa., assignor to
 Westinghouse Electric Corporation, East Pittsburgh, Pa., a corporation of Pennsylvania

Application April 13, 1948, Serial No. 20,690

6 Claims. (CL. 175—30)

1

The present invention relates to lightning arresters, and more particularly to a high-voltage lightning arrester unit of greatly reduced height, as compared to lightning arrester units of conventional design and equivalent voltage rating.

The lightning arrester unit of the present invention is especially adapted for use in high-voltage station-type lightning arresters of unit construction, although it is a complete lightning arrester in itself, and may be used alone. High-voltage station-type lightning arresters are usually of unit construction, and are made up of a suitable number of lightning arrester units, of standard voltage ratings, each of the units consisting of a suitable number of spark gap devices and valve elements, or resistors, assembled in series relation in a single stack and enclosed in a porcelain housing with metal end caps. The necessary number of these arrester units is assembled in series relation, the units being placed end-to-end in a vertical column with the end caps of adjacent units bolted together for mechanical and electrical connection. This type of construction results in a vertical column of great height as compared to its diameter, and in the higher voltage ratings, the height of the column becomes so great that it is not self-supporting, but must be supported from a suitable fixed support, such as a part of a substation structure, either by bracing or by suspension mounting. In the case of very high-voltage arresters, the required supporting structure and bracing become quite large and elaborate, and are relatively expensive, thus adding considerably to the cost of the installation. The necessity of supporting arresters in this way is, therefore, undesirable, but cannot be avoided with conventional arrester designs.

Another problem in the design of high-voltage lightning arresters is that of obtaining sufficiently uniform distribution of voltage across the tall column of arrester units. The arrester is connected between a transmission line conductor and ground, and is subjected to the line-to-ground voltage, but because of the great height of conventional lightning arresters, the voltage does not distribute itself uniformly between the individual arrester units. Satisfactory operation, however, requires reasonably uniform distribution of the voltage, and in conventional designs, this has been obtained by means of grading rings, which affect the electrostatic field surrounding the arrester, and control the capacitances between the individual arrester units and ground in such a way as to make the voltage distribution suf-

2

ficiently uniform for satisfactory operation. As the height of the arrester is increased, however, it becomes increasingly difficult to obtain sufficiently uniform voltage distribution in this way, and in high-voltage arrester units, the grading rings become quite large, so that the required clearance distance between the arrester and other apparatus is undesirably increased. When it is attempted to extend conventional lightning arrester designs to vary high voltage ratings, substantially higher than those which have been used heretofore, it is found that it is extremely difficult to provide an arrangement of grading rings which will give sufficiently uniform voltage distribution, because of the great height of the arrester.

Thus, the height of high-voltage lightning arresters of conventional construction results in the two serious problems of supporting the arrester without undue complication and expense, and of obtaining sufficiently uniform voltage distribution. When it is attempted to apply the conventional type of design to extremely high-voltage lightning arresters, these problems become very acute because of the excessive height of the arrester, and it is extremely difficult to design lightning arresters for substantially higher voltage ratings than those which have been used heretofore, if it is attempted to utilize the conventional type of construction.

The principal object of the present invention is to provide a lightning arrester unit, suitable for use in station-type lightning arresters of unit construction, which is of greatly reduced height as compared to the height of conventional lightning arrester units of equal voltage rating, so that a high-voltage lightning arrester consisting of a vertical column of the new units is relatively short, and the problems of supporting the arrester and of obtaining satisfactory voltage distribution are substantially eliminated, or at least greatly simplified.

Another object of the invention is to provide a high-voltage station-type lightning arrester of very greatly reduced height as compared to the height of a conventional lightning arrester of equivalent voltage rating.

A further object of the invention is to provide a lightning arrester unit which is of such reduced height that a vertical column of such units, even for extremely high voltage ratings, will be short enough to be self-supporting and to have satisfactory distribution of voltage between the individual arrester units without the use of grading rings.

A more specific object of the invention is to provide a high-voltage lightning arrester unit consisting of a spark gap assembly disposed centrally in a housing and surrounded by two substantially concentric stacks of annular valve elements or resistors, the gap assembly and valve elements being connected in series, so that the discharge current flows in a circuitous path and the height of the arrester is kept to a minimum even for very high voltage ratings.

The invention will be more fully understood from the following detailed description, taken in connection with the accompanying drawing, in which:

Figure 1 is a vertical, longitudinal sectional view of a high-voltage lightning arrester unit embodying the invention; and

Fig. 2 is a transverse sectional view approximately on the line II—II of Fig. 1.

The lightning arrester shown in the drawing is especially adapted for use as a unit of a high-voltage station-type lightning arrester of unit construction, although its usefulness is not necessarily limited to this particular use, since it is a complete lightning arrester in itself and may be used as such. The lightning arrester unit is contained in a housing or weather casing 1, which is preferably made of porcelain, and which is of large diameter relative to its height, as compared to the proportions of conventional lightning arrester units. The housing 1 is closed at its upper end by a metal top plate 2 which rests on the top of the housing 1, a gasket 3 being interposed between the housing 1 and the top plate 2 to seal the interior of the housing. A flanged metal top fitting or casting 4 extends over the top of the housing 1 in contact with the top plate 2, and is secured to the housing in any suitable manner, as by cementing as indicated at 5. The top fitting 4 preferably has a flat upper surface and is provided with peripheral openings 6 for the reception of mounting bolts. An annular, flanged metal bottom fitting or casting 7 is provided at the bottom of the housing 1 and is secured to it in any suitable manner, as by cementing as indicated at 8. The bottom fitting 7 has a flat bottom surface and is provided with peripheral openings 9 for mounting bolts. The bottom of the housing 1 is closed by a metal bottom plate 10 which may be secured to the bottom fitting 7 by means of bolts 11. A gasket 12 is preferably interposed between the plate 10 and the housing 1 to seal the housing.

The arrester includes a spark gap assembly 13, which may be of any suitable type, and which is shown as a porcelain-enclosed multiple-gap assembly. The gap assembly is contained in a porcelain tube 14 closed at the ends by metal end caps 15, which are sealed to the porcelain tube by soldering to a metallic glaze on the porcelain, or in any other suitable manner. The spark gap assembly consists of a plurality of metal electrodes 16 spaced apart by insulating, or high-resistance, spacers 17. The gap elements are arranged in a vertical column resting on the lower end cap 15 of the porcelain tube 14, and a spring 18 is placed in the top of the tube to hold the gap elements firmly in place and to provide good electrical contact with the upper end cap 15.

The spark gap assembly 13 is placed substantially in the center of the housing 1, and rests in a generally cup-shaped insulating member 19, which may be made of any suitable insulating material having sufficient mechanical rigidity and dielectric strength. A molded material of

suitable characteristics may be used, or the member 19 may be made of porcelain or other ceramic material. A metal contact plate 20 is provided in the bottom of the insulating member 19. The contact plate 20 may be a copper plate placed in the member 19, and preferably secured thereto in any suitable manner, or it may be a coating of copper or other metal applied to the surface of the member 19 by spraying, or other suitable method. The insulating member 19 preferably rests on a spacer block 21 of porcelain, or other insulating material, which in turn is supported on the bottom plate 10, the thickness of the spacer 21 being made such that the top of the spark gap assembly 13 is held tightly against the top plate 2 when the arrester is assembled. If desired, a spring, or spring plate, might be inserted between the top of the spark gap assembly 13 and the top plate 2 to insure good electrical contact.

The spark gap assembly 13 is surrounded by a plurality of annular valve or resistor elements 22. The valve elements 22 may be made of any suitable resistance material having valve characteristics, that is, a material which normally has very high resistance, but which sharply decreases its resistance when subjected to a high voltage, so as to permit the discharge of high surge currents, and which rapidly increases its resistance when the voltage drops, so as to pass only a small leakage current, which can easily be interrupted by the gap assembly 13. The valve elements 22 may be made of any material of this kind, such as granular silicon carbide molded to the desired size and shape with a suitable binder, such as sodium silicate, and baked. A metal contact coating is preferably applied to the end surfaces of each valve element. The valve elements 22 are annular in shape, and they are placed in a stack in the cup-shaped insulating member 19 substantially concentric with the spark gap assembly 13. The lowermost valve element 22 rests on the metal contact plate 20, so that the bottom of the stack of valve elements 22 is electrically connected to the bottom of the spark gap assembly 13, which also rests on the contact plate 20.

The arrester also includes a second stack of annular valve elements 23, which are similar to the valve elements 22, except that they are of larger diameter. The valve elements 23 are assembled in a second stack which is substantially concentric with the spark gap assembly 13 and with the first stack of valve elements 22. The stack of valve elements 23 rests directly on the bottom plate 10, so as to be in electrical contact with it, and the stack of valve elements 23 contains a greater number of valve elements than the first stack of valve elements 22, so that the tops of the two stacks are substantially in the same horizontal plane, as clearly shown in Fig. 1.

An annular insulating member 24, of generally U-shaped cross-section, is placed over the tops of the two stacks of valve elements 22 and 23. The insulating member 24 may be made of the same material as the cup-shaped insulating member 19, and it is provided with an annular metal contact plate 25 on its lower horizontal surface. The contact plate 25 may be an annular metal plate secured in the insulating member 24 in any suitable manner, or it may be a coating of copper or other metal applied to the insulating member 24 by spraying. It will be apparent that the annular contact plate or coating 25 provides electrical connection between the tops of the two concentric stacks of valve elements 22 and 23, so that

the entire assembly, consisting of the spark gap assembly 13 and the two stacks of valve elements, is connected in series between the top plate 2 and the bottom plate 10. A tubular spacer 26, which may be made of insulating material, such as porcelain, or of conducting material is placed between the annular insulating member 24 and the top plate 2 to hold the assembly firmly in place.

The inside leg 27 of the annular insulating member 24 is made longer than the outer leg so as to extend down a substantial distance between the upper parts of the spark gap assembly 13 and the inner stack of valve elements 22. Similarly, the wall of the cup-shaped insulating member 19 extends up a substantial distance between the lower parts of the two stacks of valve elements. Thus, the insulating members 19 and 24 provide insulating barriers separating those parts of the assembly which may have large potential differences between them during a discharge, so as to prevent any possibility of flash-over between parts of the assembly. It will also be noted that the spacer 21 and insulating member 19 space the bottoms of the spark gap assembly 13 and the inner stack of valve elements 22 a substantial distance from the bottom plate 10, while the tops of the two stacks of valve elements are spaced a considerable distance from the top plate 2. Thus, there is no risk of flash-over to either the top or bottom plate.

It will be apparent that the insulating members 19 and 24 provide a substantial amount of electrostatic capacitance across arrester elements, and by properly proportioning the insulating members, the capacitance across the arrester unit can be made relatively large, which materially simplifies the problem of obtaining satisfactory voltage distribution over a series-connected column of arrester units. If the spacer 26 is made of, or coated with, metal, the voltage distribution across the multiple gap assembly 13 will be somewhat better than if an insulating spacer is used, and if, in addition, a metal plate or coating is provided on the upper surface of the insulating member 24, the electrostatic capacitance across the arrester unit is increased, with resulting improvement in the voltage distribution across a column of these units.

As previously indicated, the new arrester unit may be used by itself as a lightning arrester, but it is especially adapted for use as a unit of high-voltage station-type lightning arresters. When used in this way, the necessary number of arrester units is placed end-to-end in a vertical column with the end fittings of adjacent units secured together by bolts for electrical and mechanical connection. Since the top fitting 4 of each unit is in electrical contact with the top plate 2, and the bottom fitting 7 is in electrical contact with the bottom plate 10, the entire column of arrester units is thus connected in series.

The new arrester unit contains a relatively large number of spark gaps and valve elements, and it can, therefore, be given a relatively high voltage rating. Since the arrester elements are arranged side-by-side to provide a circuitous discharge path through the unit, however, the height of the unit is very greatly reduced as compared to that of a conventional arrester unit of equivalent voltage rating in which the same number of gaps and valve elements would be arranged in a single vertical stack. Because of this reduced height, a high-voltage lightning arrester built up

of a number of these arrester units will be relatively short, as compared with arresters of conventional design, and, in general, such an arrester will be short enough to be self-supporting, and will have reasonably uniform distribution of voltage between the different arrester units without the necessity of using grading rings or other means for obtaining uniform voltage distribution.

It will be apparent that a lightning arrester unit has been provided which can be made of minimum height, for a given voltage, because of the arrangement of the arrester elements to provide a circuitous discharge path. This arrangement results in a lightning arrester unit which is of such reduced height and increased diameter, as compared to conventional arrester units, that a vertical column of the new arrester units is short enough to be self-supporting and to have reasonably uniform voltage distribution. Thus, very high-voltage lightning arresters can readily be provided without the difficulties and problems resulting from the excessive height of high-voltage lightning arresters of conventional construction.

A preferred embodiment of the invention has been shown and described for the purpose of illustration, but it will be apparent that the invention is not limited to the particular details of construction shown. It is to be understood, therefore, that the invention is not restricted to this particular embodiment, but, in its broadest aspects, it includes all equivalent embodiments and modifications which come within the scope of the appended claims.

I claim as my invention:

1. A lightning arrester comprising a generally cylindrical housing, a spark gap assembly centrally disposed in said housing, a plurality of annular valve elements in the housing disposed in a stack surrounding the spark gap assembly, a plurality of annular valve elements of larger diameter than the first-mentioned valve elements disposed in a stack in the housing surrounding the first stack, and means for electrically connecting said spark gap assembly and said two stacks of valve elements in series.

2. A lightning arrester comprising a generally cylindrical housing, a spark gap assembly centrally disposed in said housing, a plurality of annular valve elements in the housing disposed in a stack surrounding the spark gap assembly, a plurality of annular valve elements of larger diameter than the first-mentioned valve elements disposed in a stack in the housing surrounding the first stack, means for electrically connecting said spark gap assembly and said two stacks of valve elements in series, and insulating barrier means between the spark gap assembly and the first stack of valve elements and between the two stacks of valve elements.

3. A lightning arrester comprising a generally cylindrical housing, a spark gap assembly centrally disposed in said housing, a plurality of annular valve elements in the housing disposed in a stack surrounding the spark gap assembly, a plurality of annular valve elements of larger diameter than the first-mentioned valve elements disposed in a stack in the housing surrounding the first stack, means for electrically connecting the bottom of the spark gap assembly to the bottom of the first stack of valve elements, and means for electrically connecting the top of the first stack of valve elements to the top of the second stack of valve elements.

4. A lightning arrester comprising a generally cylindrical housing, a spark gap assembly centrally disposed in said housing, a plurality of annular valve elements in the housing disposed in a stack surrounding the spark gap assembly, a plurality of annular valve elements of larger diameter than the first-mentioned valve elements disposed in a stack in the housing surrounding the first stack, means for electrically connecting the bottom of the spark gap assembly to the bottom of the first stack of valve elements, means for electrically connecting the top of the first stack of valve elements to the top of the second stack of valve elements, and insulating barrier means between at least the upper portions of the spark gap assembly and the first stack of valve elements and between at least the lower portions of the two stacks of valve elements.

5. A lightning arrester comprising a generally cylindrical housing, a spark gap assembly centrally disposed in said housing, a plurality of annular valve elements in the housing disposed in a stack surrounding the spark gap assembly, a plurality of annular valve elements of larger diameter than the first-mentioned valve elements disposed in a stack in the housing surrounding the first stack, means for electrically connecting the bottom of the spark gap assembly to the bottom of the first stack of valve elements, means for electrically connecting the top of the first stack of valve elements to the top of the second stack of valve elements, a generally cup-shaped insulating member in the bottom of the housing, the spark gap assembly and the first stack of the valve elements being disposed within said cup-shaped member, and the cup-shaped member ex-

tending upward between the two stacks of valve elements, and an annular insulating member extending over the tops of the two stacks of valve elements, said annular insulating member having a portion extending downward between the first stack of valve elements and the spark gap assembly.

6. A lightning arrester comprising a generally cylindrical housing, a spark gap assembly centrally disposed in said housing, a plurality of annular valve elements in the housing disposed in a stack surrounding the spark gap assembly, a plurality of annular valve elements of larger diameter than the first-mentioned valve elements disposed in a stack in the housing surrounding the first stack, a generally cup-shaped insulating member in the bottom of the housing, the spark gap assembly and the first stack of valve elements being disposed within said cup-shaped member, and the cup-shaped member extending upward between the two stacks of valve elements, means on the cup-shaped member for effecting electrical connection between the bottom of the spark gap assembly and the bottom of the first stack of valve elements, an annular insulating member extending over the tops of the two stacks of valve elements, said annular insulating member having a portion extending downward between the first stack of valve elements and the spark gap assembly, and means on the annular insulating member for effecting electrical connection between the tops of the two stacks of valve elements.
